UNITED STATES PATENT OFFICE

BENJAMIN F. CONNER, OF HARTFORD, CONNECTICUT, ASSIGNOR TO COLT'S PATENT FIRE ARMS MANUFACTURING COMPANY, OF HARTFORD, CONNECTICUT, A CORPORATION OF CONNECTICUT

ELECTRICAL CONNECTION PLUG

Application filed October 18, 1927, Serial No. 227,026. Renewed July 15, 1930.

The invention relates particularly to electrical connection plugs such as are commonly used at the end of a conductor cord for providing an electrical connection to various current using appliances such as electric irons, electric toasters, electric heaters, and the like.

It is well known that connection plugs of this class frequently become very hot by reason of heat transmitted from the appliances with which they are used and it is also well known that the frictional engagement of such plugs with the contacts of the appliances is frequently such as to offer considerable resistance tending to prevent removal. By reason of the high temperature and the considerable frictional resistance the removal of a plug by taking direct hold thereof is frequently a matter of much discomfort and difficulty. To avoid such discomfort and difficulty the user frequently pulls on the cord with the result that the cord is broken or detached from its terminals. The principal object of the present invention is to provide a plug of this class having an improved movably connected handle so formed as to be adapted for convenient manual engagement to pull the plug away from the appliance, the construction of the said handle and the position of the manually engageable portion thereof being such that the last said portion is always at a comfortable temperature notwithstanding the heating of the plug body. In accordance with the invention the handle is preferably provided with a longitudinal hole therethrough for receiving the conductor cord, the handle thus taking the place of the usual guard or support formed of coiled wire.

A more specific object of the invention is to provide certain improved details of mechanical construction which reduce the cost of manufacture of the several parts and which facilitate assembly.

Other objects of the invention will be apparent from the following specification and claims.

In the accompanying drawing I have shown two embodiments of the invention, but it will be understood that the drawing is in-

tended for illustrative purposes only and is not to be construed as defining or limiting the scope of the invention, the claims forming a part of this specification being relied upon for that purpose.

Of the drawing:

Fig. 1 is a perspective view of a connection plug embodying the invention.

Fig. 2 is a view showing that end of the plug which is at the right in Fig. 1.

Fig. 3 is a vertical sectional view taken along the line 3—3 of Fig. 2.

Fig. 4 is a vertical sectional view taken along the lines 4—4 of Figs. 2 and 3.

Figs. 5 and 6 are views similar respectively to Figs. 3 and 4 but showing an alternate embodiment of the invention.

Referring to the drawing, particularly to Figs. 1 to 4 thereof, 1 represents the main body of the plug which is formed of insulating material. The exact details of construction of the body 1 may be varied but I prefer to construct the said body with two separate companion parts 1^a and 1^b which are positioned at opposite sides of a longitudinal plane of division. The two parts are normally held in the proper relative positions by means of screws 2, 2. Carried by the body 1 are two separate contacts adapted to be detachably engaged for electrical connection purposes with the supply contacts of a current using appliance. The details of the contacts may be varied but for purposes of illustrating the invention I have shown female contacts 3 and 4 which may be of conventional form. As illustrated the body parts 1^a and 1^b are provided with suitable registering recesses 5, 5 and 6, 6 in which the contacts 3 and 4 are respectively located. As shown each contact 3 or 4 comprises two separate metallic parts held in place by means of a screw 7. The two screws 7, 7 for the two contacts also serve as terminals for establishing electrical

and mechanical connection with the two conductors of a conductor cord such as C. I have shown the two conductors as extending directly to the said screws, but it will be understood that the electrical con-

nection may be indirect, as for instance through a suitable switch.

Pivottally connected with the body of the plug, preferably at a position substantially opposite the said contacts 3 and 4, is a handle 8 which is preferably inflexible and is provided near its outer end with means conveniently engageable manually for pushing the plug into place on the associated 10 appliance or for pulling it therefrom. The means for forming a pivotal connection between the handle 8 and the body of the plug may be varied but when the said body comprises two separate parts 1^a and 1^b I preferably form the said parts with suitable interior recesses near the end and I form the said handle 8 with a portion which is adapted to be seated in the recesses so as to form the required pivotal connection. As illustrated, particularly in Figs. 3 and 4, the two body parts are formed with registering substantially cylindrical recesses at 9 and 9^a and the handle 8 is provided with substantially cylindrical trunnions 10 and 10^a seated 20 respectively in the said recesses. The said handle 8 extends between the said parts 1^a and 1^b of the body, which parts are flared outward at 11 and 11^a respectively to permit pivotal movement of the handle 8 through 30 the range indicated by dot-and-dash lines in Fig. 4. The said body parts at 11 and 11^a serve as stops to limit the pivotal movement of the handle.

The handle 8 is provided with a central 35 longitudinal hole 13 therethrough for the reception of the cord C. As clearly shown in Fig. 3 the cord C extends through the hole 13 in the handle and the inner ends of the two conductors of the cord are secured to the terminals 7, 7. Thus the handle 8 serves as a guard for the cord, taking the place of the usual coiled wire guard. Preferably the hole 13 terminates at its inner end in a recess 13^a located between the two trunnions 10 and 10^a. The said recess 45 13^a serves to permit the diverging of the conductors of the cord and to thereby facilitate the connection thereof with the terminals 7, 7.

As already stated the handle 8 is provided 50 near its outer end with means conveniently engageable manually for exerting a pull to remove the plug from the appliance. The details of this manually engageable means may be varied but I prefer to provide the handle 8 with two oppositely extending projections 12 and 12^a which are conveniently engageable by two fingers of the hand of the user. The manually engageable portion of 55 the handle 8 is sufficiently spaced from the body of the plug to avoid the transmission thereto of any considerable amount of heat from the plug, the result being that the said manually engageable portion is never above 60 a comfortable temperature. Ordinarily and

preferably, in order to further guard against any possible excess temperature of the said manually engageable means, I construct the said handle 8 of a material which has relatively low heat conductivity. The handle 8 is particularly adapted to be formed of mold- 70 ed material such as a phenolic condensation compound.

It will be obvious that when it is desired to remove the plug from the appliance the user 75 can conveniently engage the manually engageable projections 12, 12^a, ordinarily engaging the respective projections with two fingers, so as to conveniently pull the plug away from the appliance. By reason of the 80 low temperature of the end portion of the handle there is no discomfort by reason of excessive temperature and the said portion is so shaped that a considerable pull can be exerted without any difficulty. I thus avoid the difficulties which are commonly incident 85 to the removal of the ordinary plugs, which become highly heated and which are difficult to firmly grasp, and I avoid any possible necessity for the user to pull on the cord. 90 Obviously the said projections 12 and 12^a may also be used for engagement by the hand to push the plug into place.

From the foregoing description it will be apparent that the element 8 serves not only 95 as a handle but also as a guard for the cord. With my improved construction it is possible to thread the cord through the hole in the handle prior to the final assembly of the handle with the two body parts 1^a and 1^b, and 100 the inner ends of the conductors forming the cord C can then be connected to the respective terminals 7, 7. Thereafter the two body parts 1^a and 1^b can be brought into engagement with each other to enclose the contacts, the terminals and the inner ends of the cord conductors and at the same time to engage and retain the handle in such a way as to 105 permit the desired pivotal movement thereof.

In Figs. 5 and 6 I have shown a somewhat 110 different embodiment of the invention wherein the handle is connected to the plug body for pivotal movement in any direction, instead of being connected thereto for movement about a single transverse axis as shown 115 in Figs. 1 to 4. As illustrated in Figs. 5 and 6 the plug has a body 14 comprising two similar parts 14^a and 14^b connected by screws 2, 2. Mounted in the body are contacts 3 and 4 which may be exactly the same in construction as those already described, being held in place by screws 7, 7. The body parts 14^a and 14^b, instead of being provided with substantially cylindrical recesses such as 9 and 9^a, are provided with recesses 15 and 16 having inner concave faces which conform throughout to the surface of a sphere. A handle 17 is provided having at its inner 120 end a ball 18 of such size as to be adapted to fit within the socket formed by the recesses 125 120

15 and 16 in the two body parts 14^a and 14^b. The two said body parts are so formed as to permit the said handle 17 to have pivotal movement in any direction within the limits indicated by dot-and-dash lines in Figs. 5 and 6. The handle 17 may be otherwise the same in construction as the handle 8 and repetition of the description is unnecessary.

It will be observed that with the construction shown in Figs. 5 and 6 the handle 17 may be moved angularly in any direction and in addition may be turned about its longitudinal axis so that the projections 12 and 12^a may extend in any desired direction as the user may find most convenient.

What I claim is:

1. In an electrical connection plug, the combination of two separate contacts detachably engageable with the supply contacts of a current using appliance, an inflexible handle having a longitudinal hole therethrough and provided at one end with a connection means permitting pivotal movement, two terminals supported independently of the handle and electrically connected with the respective contacts, a flexible conductor cord extending through the said hole in the handle and having the conductors thereof directly connected at their inner ends to the respective terminals, and two companion body parts connectible with each other after the cord has been inserted through the handle and has been connected to the terminals, the said body parts when so connected with each other serving to substantially enclose the contacts and terminals and the adjacent portions of the cord and further serving to engage between them at least a portion of the aforesaid handle connection means so as to retain the handle and permit relative pivotal movement thereof.

2. In an electrical connection plug, the combination of two separate contacts detachably engageable with the supply contacts of a current using appliance, an inflexible handle having a longitudinal hole therethrough and provided at one end with transversely projecting integral pivot means, two terminals supported independently of the handle and electrically connected with the respective contacts, a flexible conductor cord extending through the said hole in the handle and having the conductors thereof directly connected at their inner ends to the respective terminals, and two companion body parts connectible with each other after the cord has been inserted through the handle and has been connected to the terminals, the said body parts when connected with each other serving to substantially enclose the contacts and terminals and the adjacent portions of the cord and the said body parts being provided with recesses for receiving the pivot means of the handle so as to retain the handle and permit relative pivotal movement thereof.

3. In an electrical connection plug, the combination of an insulating body comprising two companion parts positioned at opposite sides of a longitudinal division plane and shaped near one end to provide two substantially cylindrical interior recesses having their axes in alignment with each other, separate contacts carried by the body near the other end thereof between the two said parts and detachably engageable with the supply contacts of a current using appliance, and a handle at the first said end of the plug provided with two aligned substantially cylindrical trunnions seated in the said body recesses to form a pivotal connection with the body and having a longitudinal hole extending entirely therethrough, and terminals carried by the body independently of the handle and positioned for connection with a conductor cord extending entirely through the said hole in the handle.

4. In an electrical connection plug, the combination of an insulating body comprising two companion parts positioned at opposite sides of a longitudinal division plane and shaped near one end to provide two substantially cylindrical interior recesses having their axes in alignment with each other, separate contacts carried by the body near the other end thereof between the two said parts and detachably engageable with the supply contacts of a current using appliance, terminals in electrical connection with the said contacts and respectively connectible directly with the conductors of a flexible cord, and a handle at the first said end of the plug provided with two aligned substantially cylindrical trunnions seated in the said body recesses to form a pivotal connection with the body, the said handle having a longitudinal hole extending entirely therethrough and terminating at its inner end in a recess located between the trunnions which hole and recess serve to receive the cord and to permit the diverging of the conductors thereof for connection with the said terminals.

5. In an electrical connection plug, the combination of an insulating body comprising two companion parts positioned at opposite sides of a longitudinal division plane and shaped near one end to provide two substantially cylindrical interior recesses having their axes in the said division plane and in alignment with each other, separate contacts carried by the body near the other end thereof between the two said parts and detachably engageable with the supply contacts of a current using appliance, terminals in electrical connection with the said contacts and respectively connectible directly with the conductors of a flexible cord, a handle at the first said end of the plug provided with two aligned substantially cylindrical trunnions seated in the said body recesses to form a pivotal connection with the body and having a

longitudinal hole extending entirely therethrough for receiving the said conductor cord, and projections on the said body parts at opposite sides of the handle serving as stops to limit pivotal movement.

6. In an electrical connection plug, the combination of an insulating body, separate contacts carried by the body near one end thereof detachably engageable with the supply contacts of a current using appliance and electrically connectible respectively with the conductors of a flexible cord, and a handle pivotally connected to the body at the opposite end thereof and having a longitudinal hole therethrough for the said conductor cord, the said handle being provided near its outer end with projections extending transversely in opposite directions and conveniently engageable manually for exerting a push to connect the plug with the appliance or a pull to remove it therefrom.

7. In an electrical connection plug, the combination of an insulating body comprising two companion parts positioned at opposite sides of a longitudinal division plane and shaped near one end to provide two substantially cylindrical interior recesses having their axes in the said division plane and in alignment with each other, separate contacts carried by the body near the other end thereof of between the two said parts, the said contacts being adapted to be detachably engageable with the supply contacts of a current using appliance and being electrically connectible respectively with the conductors of a flexible cord, and a handle at the first said end of the plug provided with two aligned substantially cylindrical trunnions seated in the said body recesses to form a pivotal connection with the body and having a longitudinal hole extending entirely therethrough for receiving the said conductor cord, the said handle being provided near its outer end with projections extending transversely in opposite directions substantially parallelly with the axis of the trunnions and conveniently engageable by two fingers of the user for exerting a pull to remove the plug from the appliance.

8. As an article of manufacture, an inflexible one-piece handle member for an electrical connection plug hollow from end to end for the reception of a conductor cord and provided at one end with an integral radially projecting pivot means and at the other end with integral radially projecting means conveniently engageable by the fingers of the user.

9. A handle member as set forth in claim 8, wherein the pivot means consists of two oppositely extending substantially cylindrical trunnions.

10. A handle member as set forth in claim 8, wherein the pivot means consists of two oppositely extending substantially cylindri-

cal trunnions and wherein the finger engageable means consists of two oppositely extending projections substantially parallel with the said trunnions.

11. As an article of manufacture, a half-body part for an electrical connection plug formed near one end with two similar longitudinal recesses for the partial reception of electrical contacts and formed near the other end with a central longitudinal recess for the partial reception of a handle member and with two transverse semi-cylindrical recesses spaced from the last said end and joining the central recess at opposite sides thereof, the said transverse recesses having a common axis perpendicular to the axis of the central recess and being adapted for the partial reception of substantially cylindrical transverse trunnions formed integrally on the said handle member.

12. In an electrical connection plug, the combination of two separate contacts detachably engageable with the supply contacts of a current using appliance, an inflexible handle having a longitudinal hole therethrough and provided at one end with a connection means permitting pivotal movement in any direction, two terminals supported independently of the handle and electrically connected with the respective contacts, a flexible conductor cord extending through the said hole in the handle and having the conductors thereof directly connected at their inner ends to the respective terminals, and two companion body parts connectible with each other after the cord has been inserted through the handle and has been connected to the terminals, the said body parts when so connected with each other serving to substantially enclose the contacts and terminals and the adjacent portions of the cord and further serving to engage between them at least a portion of the aforesaid connection means so as to retain the handle and permit pivotal movement thereof in any direction as aforesaid.

13. In an electrical connection plug, the combination of an insulating body, two separate contact elements carried by the body near one end thereof and detachably engageable with the supply contacts of a current using appliance, a handle having a longitudinal hole therethrough and having at its outer end oppositely extending projections conveniently engageable manually, the said handle being connected with the insulating body at the end thereof opposite the said contacts for rotation with respect to the said body and with respect to the said contact elements about a longitudinal axis so as to bring the said projections into any desired position of rotative adjustment about the said axis, two terminals supported on the insulating body independently of the handle and electrically connected with the respective contact elements, and a flexible conductor cord extend-

ing through the hole in the handle and having the conductors thereof respectively connected at their inner ends directly to the said terminals.

- 5 14. In an electrical connection plug, the combination of an insulating body, two separate contact elements carried by the body near one end thereof and detachably engageable with the supply contacts of a current
- 10 using appliance, an inflexible handle having a longitudinal hole therethrough and having at its outer end oppositely extending projections conveniently engageable manually, the said handle being connected with the insulating body at the end thereof opposite the said contacts for universal pivotal movement with respect to the said body and with respect to the said contact elements and also for rotative movement with respect thereto
- 15 about a longitudinal axis so as to bring the handle into any desired angular position with respect to the body and so as to bring the said projections into any desired position of rotative adjustment about the said longitudinal axis, two terminals supported on the insulating body independently of the handle and electrically connected with the respective contact elements, and a flexible conductor cord extending through the hole in
- 20 the handle and having the conductors thereof respectively connected at their inner ends directly to the said terminals.
- 25
- 30

In testimony whereof I have hereunto set my hand this 13th day of October, 1927.

35 BENJAMIN F. CONNER.
